US0D1062080S

(12) **United States Design Patent** (10) **Patent No.:** **US D1,062,080 S**
(45) **Date of Patent:** **** Feb. 11, 2025**

- (54) **FIRE EXTINGUISHER BRACKET**
- (71) Applicant: **Enming Zhou, Zhejiang (CN)**
- (72) Inventor: **Enming Zhou, Zhejiang (CN)**
- (*) Notice: Patent file contains an affidavit/declaration under 37 CFR 1.130(b).
- (**) Term: **15 Years**
- (21) Appl. No.: **29/880,685**
- (22) Filed: **Jul. 26, 2023**
- (51) LOC (15) Cl. **29-01**
- (52) U.S. Cl. **USPC D29/130**
- (58) **Field of Classification Search**

(57) **CLAIM**

The ornamental design for a fire extinguisher bracket, as shown and described.

DESCRIPTION

FIG. 1 is a front perspective view of a fire extinguisher bracket, showing my new design;

FIG. 2 is a rear perspective view thereof;

FIG. 3 is a front elevational view thereof;

FIG. 4 is a rear elevational view thereof;

FIG. 5 is a left side view, the right side view being a mirror image of FIG. 5;

FIG. 6 is a top plan view thereof;

FIG. 7 is a bottom plan view thereof; and,

FIG. 8 is a front perspective view of the fire extinguisher bracket, indicating the usage environment.

The broken lines in FIG. 8 illustrate usage environment and form no part of the claimed design.

1 Claim, 7 Drawing Sheets
